UNITED STATES PATENT OFFICE.

JOSEPH JOHN NELIS, OF BROOKLYN, NEW YORK, ASSIGNOR TO FOSTER WHEELER CORPORATION, OF NEW YORK, N. Y., A CORPORATION OF NEW YORK.

SUPERHEATER FOR SCOTCH BOILERS.

Application filed February 28, 1924. Serial No. 695,679.

The primary object of my present invention is to provide a boiler of the Scotch or analogous type with improved means for superheating the steam generated. Further objects 5 of the invention, and advantages obtained from its use are set forth in the following descriptive matter, in which, and in the accompanying drawings, I have described and illustrated a preferred embodiment of the invention, the various features of novelty of 10 which are pointed out with particularity in the claims annexed to and forming a part of this specification.

Of the drawings:

Fig. 1 is an elevation in section on the line 15 1—1 of Fig. 3;

Fig. 2 is a partial section on the line 2—2 of Fig. 1; and

Fig. 3 is a rear elevation.

In the drawings I have illustrated the use 20 of my invention in a conventionally illustrated wet back Scotch boiler provided with a central combustion chamber B and two side combustion chambers B' located within the boiler shell A. Each of the combustion chambers B and B' comprises a horizontally disposed cylindrical body portion and a compartment B² adjacent the rear end of the boiler. To the front wall B³ of the compartment B² is secured the rear end of the corrugated metal cylinder B¹⁰ which forms the 25 wall of the body portion of the combustion chamber. The usual flue tubes C are provided to pass hot gases from each combustion chamber to the breeching D leading to the boiler stack. The tubes C are connected at 30 their rear ends to the front walls B³ of the compartments B², and at their front ends are connected into the front end wall of the boiler shell A in the usual manner. The boiler may 35 be heated by the combustion of solid fuel on grates in the cylindrical portions of the combustion chambers B and B', or by the combustion therein of oil or gas in the usual manner, but, as the provisions for thus heating the boiler are well known, and the use of the present invention does not depend on their exact character, they are not illustrated in the drawings.

The steam generated by the boiler is superheated in a superheater comprising elements F located in each compartment B². As shown, the superheater elements F are arranged directly in front of the upper portion of the

rear wall B⁴ of each compartment B², and 55 in the preferred construction illustrated, each superheater element F comprises a tube F¹ having a vertically disposed body portion and horizontally disposed end portions which extend horizontally through the corresponding 60 chamber wall B⁴ and through the rear end of the boiler shell proper, and through stay tubes G connecting those walls and extending through the water space between them. The body portion of each tube F¹ is surrounded 65 by a casing divided transversely to the length of the tube into comparatively short sections and formed of metal blocks F' each having a passage for the corresponding tube body F¹. The casing sections F' are advantageously 70 formed of cast iron or steel shrunk on the tubes F¹, and advantageously some of the sections F' have supporting bolts F³ welded to their rear sides which extend through the rear wall B⁴ of the corresponding compartment B² and through the rear wall of the boiler shell, where they are provided with nuts F⁴. The portions of these bolts traversing the water space between the rear end of the boiler shell and the corresponding wall 75 B⁴ are surrounded by stay tubes G'. The various casing sections F' unite to form a heavy metallic wall lining the upper portion of the rear wall B⁴ of the corresponding compartment B². As shown, the lower portion of 80 the rear wall B⁴ of each compartment B² is provided with a fire brick lining E, but this may be omitted if desired.

As shown, the headers to which the end 85 portions of the superheater tubes F¹ are connected are divided into sections H, H', H², and H³, supported by brackets I secured to the rear end of the boiler shell. The upper 90 ends of the tubes F¹ for one of the side compartments B² are connected into the header section H, and the lower ends of the tubes F¹, as well as the lower ends of the tubes F¹ for the central compartment B², are 95 connected to the header section H'. The header H has one end closed and has its other end 100 connected to the boiler steam pipe A' while the header H' is closed at both ends. The upper ends of the tubes F¹ of the elements F in the central compartment B² are connected 105 to the header section H', to which are also connected the upper ends of the tubes F¹ for the compartment B² at the opposite side of the boiler from that at which the header H

- is located. The lower ends of the last mentioned tubes F^2 are connected to the header section H^3 . Both ends of the header section H^2 are closed, while one end of the header section H^3 is closed and its other end is connected to the delivery pipe (not shown) for the superheated steam. With the described construction, the superheater comprises three passes for the steam: one through the tubes F^2 connecting the header sections H and H' , one through the tubes F^2 connecting the header sections H' and H^2 , and a final pass through the tubes F^2 connecting the header sections H^2 and H^3 . The lower header sections H' and H^3 may well be provided with valved drain connections M , as shown, and the steam pipe A' will ordinarily be connected to a safety valve (not illustrated).
- Piping K shown as comprising a separate branch containing a cut-off valve K' leading to each of the header sections H and H^2 , connects the latter to the interior of the boiler shell above the water level therein. Piping L , including a separate branch containing a cut-off valve L' leading to each of the header sections H' and H^3 , connects the latter to the interior of the boiler shell adjacent the bottom of the water space. Advantageously the discharge end L^2 of the piping L opens to the water space of the boiler beneath the cylindrical portion of the combustion chamber B at a point intermediate the ends of the latter.
- In the contemplated normal operation of the superheater boiler illustrated, the superheater elements absorb some heat by contact with and conduction from the hot gases passing through the compartments B^2 , but in large part are heated by heat radiated to the entire front face of the superheater by the hot gases passing through the compartments B^2 . It will be observed, moreover, that, while the superheater elements F in the central combustion chamber B have their lower ends located at or about the level of the top of the cylindrical portion of that combustion chamber, there is opportunity nevertheless, for the direct radiation of heat through the open end of said cylindrical combustion chamber portion to the superheater elements as well as from the open ends of the cylindrical portions of the side combustion chambers to a level well below the tops of which the lower ends of the corresponding superheater elements extend. The described location of the radiant heat absorbing superheaters insures a relatively large superheating effect with a comparatively small amount of superheating surface and without adding to the draft loss in the boiler. The described location of the superheating protects the portions of the combustion chamber walls B^4 back of them against excessive heat absorption which causes burning of stays, stay nuts, and when heavily scaled, of the rear combustion chamber sheets. The described location and ar-

rangement of the superheaters reduces the repairs of stay bolts, stay nuts and sheets which would otherwise be required. The vertical disposition of the superheater tubes permits of the ready and effective drainage of the superheater as a whole, when this is required, by the simple drainage provisions illustrated. The superheating effect can be modified should this be necessary, by opening one or both of the valves L' to allow the discharge of the small amount of water into the superheater required to produce the desired reduction in superheat. The primary purpose of the piping K and L , however, is to permit the superheater to be used as additional boiler heating surface when this is desirable, and particularly when the boiler is being heated up. With the valves K' and L' open, the heating up of the boiler to raise steam from cold water is hastened by the added and highly effective heating surface formed by the superheater and the rapidity with which the boiler can be safely heated up is increased by the improved water circulation in the boiler proper due to the action of superheater surface. As the water in the vertical portions of the tubes F^2 is heated up and its density thereby decreased water is drawn from beneath the horizontal portion of the central combustion chamber through the open pipe end L^2 at a comparatively rapid rate, and is discharged at the same into the upper portion of the boiler shell through the piping K . The improved water circulation in the boiler thus provided substantially increases the rapidity with which the boiler may be heated up without risk of the usual severe temperature strains set up between the upper and lower portions of Scotch type boilers due to lack of circulation of its contained water.

While in accordance with the provisions of the statutes I have illustrated the best form of my invention now known to me, it will be apparent to those skilled in the art that changes may be made in the form of the apparatus disclosed without departing from the spirit of my invention as set forth in the appended claims, and that certain features of my invention may sometimes be used with advantage without a corresponding use of other features.

Having now described my invention, what I claim as new and desire to secure by Letters Patent is:

1. In a boiler of the type comprising an internal combustion chamber with a portion of the wall thereof separated from the boiler shell by a portion of the water space and stay tubes connecting said wall portion and shell, the improvement which consists in a superheater formed of tubular elements having body portions arranged to form a lining for a substantial part of said wall portion and having transversely extending sup-

ports connected to the body portions at intervals along their lengths and extending through said stay tubes.

2. In a boiler of the type comprising an internal combustion chamber with a horizontal portion opening at the front of the boiler and communicating at its rear end with an upwardly extending compartment connected to flues running back to the front 10 of the boiler, the improvement which consists in a superheater composed of tubular elements vertically disposed in the said compartment, an upper header to which the upper ends of said elements are connected, a

lower header to which the lower ends of said elements are connected, piping for passing the steam to be superheated to the superheater, a valved pipe connection from the lower header to the boiler water space, opening into the latter below said horizontal portion of said combustion chamber, and a valved connection from the upper header to the boiler opening into the latter adjacent the water level therein. 15

Signed at New York city, in the county of 25 New York and State of New York, this 26th day of February, A. D. 1924.

JOSEPH JOHN NELIS.
